(57) **CLAIM**

The ornamental design for a glasses cleaning kit, as shown and described.

DESCRIPTION

FIG. 1 is a front, right and top perspective view of a glasses cleaning kit showing my new design.

FIG. 2 is a rear, right and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an exploded view thereof; and,

FIG. 10 is an enlarged view of a glasses cleaning kit taken from the circle part in FIG. 9.

The broken lines in the drawings depict portions of the glasses cleaning kit and form no part of the claimed design. The dashed broken lines shown in FIGS. 9–10 indicates cutoff boundaries for the enlarged detailed views and form no part of the claimed design.
